UNITED STATES PATENT OFFICE.

ALBERT B. STAFFORD, OF TROY, NEW YORK.

COLLAR.

1,137,241.

Specification of Letters Patent. Patented Apr. 27, 1915.

Application filed February 1, 1913. Serial No. 745,592.

To all whom it may concern:

Be it known that I, ALBERT B. STAFFORD, a citizen of the United States, residing at Troy, in the county of Rensselaer and State of New York, have invented certain new and useful Improvements in Collars, of which the following is a full, clear, and exact description, such as will enable others skilled in the art to which it appertains to 10 make and use the same.

This invention relates to collars for garments, and with respect to its more specific features, to detachable shirt collars involving a fold at the front proximate end portions thereof.

The object of the invention is to provide a practical collar of the character referred to in which the proximate ends thereof will be efficiently maintained in set position under the exigencies of use.

Other objects will be in part obvious and in part pointed out hereinafter.

The invention accordingly consists in the features of construction, combinations of 25 elements and arrangement of parts which will be exemplified in the construction hereinafter set forth, and the scope of the application of which will be indicated in the following claims.

30 In the accompanying drawing wherein is illustrated the preferred embodiment of the invention and wherein similar reference characters refer to similar parts throughout the several views, Figure 1 is a perspective view of a collar embodying the invention; Fig. 2 is a front view of the collar when in fastened position on the shirt; and Fig. 3 illustrates a detail of the bifurcated end looking at the bottom edge.

40 In folded collars, and especially in folded collars of substantial height, that is to say, of such a height as to give the appearance of a standing collar, it is found that the upper corners of the collar, though designed to come so close together as to abut or occupy a definite laterally spaced relation, will not maintain the predetermined designed position in use. The movements of the wearer, the manner in which the collar is manipulated when being applied to the shirt, and the frequent distortion due to poor laundrying seem to play a part in causing the collar to assume an unsymmetrical and undesigned position. This invention is designed to avoid the above and other relevant objections.

In the collar illustrated, the numeral 1 indicates an inner band of substantial height so as to position the top edge of the collar at such a distance from the shirt as to have 60 the effect, in height, of a standing collar.

The numeral 2 indicates an outer band which is the main visible portion of the collar when in use, and the upper edges of the bands 1 and 2 are connected closely adjacent their upper edges, as usual, the outer band 2 being folded into a position opposite the inner band, as illustrated in the drawing. When the collar is fastened and in position on the shirt, the end edges 3 70 and 4 of the outer band may be designed to occupy either a position close to each other or separated a definite amount, but the opposite end portions of the inner band are designed to overlap each other when in position upon the shirt.

75 Collars may be composed of one or more thicknesses of material, and in the present instance four thicknesses of material are illustrated, as this construction lends itself readily to the embodiment of the invention. The inner band of the collar is provided with the usual buttonhole 5 in the back, and the opposite ends of the inner band are provided with buttoning portions or tabs 6 and 80 85

7 each of which extends beyond the edges 4 and 3 respectively of the outer band. One of said end portions, as 6, comprises a single tab composed of the four thicknesses of material referred to, but the four thicknesses of the opposite end portion are secured together in pairs, 8 and 9, the bifurcation thus formed extending throughout the height of the inner band at the tab portion and providing a pocket or slot for the 90 95

reception of the end portion 6 when the collar is fastened. Preferably the end portions 8 and 9 provide buttoning tabs which are independent from each other from the corner 10 through the edges indicated by the numerals 10, 11, 12, 13 and 10, 14, 15, 13, and said end portions 8 and 9 meet in a line of sewing 16 which extends in the inner band very closely from adjacent the upper edge 100 to the lower edge thereof and at a relatively steep angle to each edge, as illustrated, for a purpose hereinafter referred to. The tab 6 is provided with a buttonhole 17 and the tabs 8 and 9 are provided with corresponding buttonholes 18 and 19. The upper edge 105 110 115 20 of the end portion 6 is disposed at such an angle that when the collar is in position

on the shirt with the tab 6 between the tabs 8 and 9, said upper edge 20 will lie closely adjacent and substantially parallel to the folded or connected edge of the collar, as 5 illustrated in Fig. 2. The upper edges 21 and 22 of each of the tabs 8 and 9 are also so shaped as to lie closely adjacent and substantially parallel with the folded or connected edge in the opposite end portion of 10 the collar. The line of sewing 16 forms the rear edge of the pocket, and is disposed beneath the outer band so that when the collar is fastened the slight bulge due to the insertion of the tab 6 will be concealed by the 15 outer band.

The collar is applied to the shirt by first inserting the rear collar button in the buttonhole 5. When the buttonhole 19 of the inner tab 9 is engaged with the front collar 20 button; then the tab 6 is engaged therewith, and last the tab 8. When in position the collar will present a neat and attractive appearance, and as the tabs 6 and 7 are substantially the same in height as the height 25 of the inner band there will be little tendency for the inner band to bulge forwardly at the upper edge, which so frequently happens in folded collars of the type now in use. The corners 10 and 23 where the inner 30 and outer bands meet will be held in substantially fixed relative position, either close together or spaced a short distance, depending upon the design of the collar, the upper edges 20, 21 and 22 of the tabs, lying closely 35 adjacent the line of the fold in the respective opposite end portions of the collar, the tab 8 being between the inner and the outer bands, and the tab 9 on the outside face of the inner band, so that any tendency of the 40 tab 8 to bulge outwardly is resisted by the tab 9 to which it is in a measure connected through the front collar button. The edge 16 of the pocket will form an abutment for the end edge of the tab 6 so that undue 45 movement of the tab 6 around the front collar button as an axis will be resisted. Thus by the above described construction is accomplished, among others, the objects hereinbefore stated.

50 As many changes could be made in the above construction and many apparent widely different embodiments of this invention could be made without departing from

the scope thereof, it is intended that all matter contained in the above description or 55 shown in the accompanying drawings shall be interpreted as illustrative and not in a limiting sense.

Having described my invention, what I 60 claim as new and desire to secure by Letters Patent is:

1. A collar comprising an inner band of substantial height, an outer band of substantial height opposite the inner band, connected to the upper edge of the inner band and free at its lower edge, said inner band provided at opposite ends with buttoning portions of substantially the height of the inner band, one of said ends having a pocket extending beneath the outer band, and the 70 other end being adapted to lie in said pocket when the collar is fastened, said last-mentioned end having an edge adapted to lie closely adjacent the proximate edge of the 75 said pocket.

2. A collar comprising an inner band of substantial height, an outer band of substantial height opposite the inner band, connected to the upper edge of the inner band, said inner band provided at opposite ends with 80 buttoning portions of substantially the height of the inner band, one of said ends being bifurcated throughout the height of the inner band, to receive the other, said bifurcated end providing an upper edge 85 adapted to lie closely adjacent the upper edge of the collar between said bands.

3. A collar comprising an inner band, an outer band opposite the inner band connected to the upper edge of the inner band, said inner band provided at opposite ends with buttoning tabs of substantially the height of the inner band, one of said tabs being bifurcated throughout the height of the inner band to receive the other, the upper edges of 90 the tabs formed by the bifurcation being shaped to lie closely adjacent the upper edge 95 of the collar, one between the inner and the outer bands and the other on the outside of the inner band opposite its companion tab. 100

In testimony whereof I affix my signature, in the presence of two witnesses.

ALBERT B. STAFFORD.
